APPARATUS FOR PROCESSING THREAD

Walter F. Knebusch, Rocky River, and Alden H. Burkholder, Cleveland, Ohio, assignors to Industrial Rayon Corporation, Cleveland, Ohio, a corporation of Delaware

Application October 24, 1938, Serial No. 236,722

6 Claims. (Cl. 18—8)

This invention relates to the processing of thread or the like, hereinafter referred to as "thread"; more particularly, to the continuous processing of artificial silk thread.

In the manufacture of multiple filament viscose artificial silk thread, in connection with which the present invention will be described, it is necessary to make economical use of the various treating liquids employed in the processing of the thread, this because of the large quantities which must be employed and the comparatively high cost of the treating liquids. Even the cost of the water used in the manufacture of multiple filament viscose artificial silk thread is an important factor, not only because of the large quantities used for the several washing treatments but because it is often necessary to treat the water in order to obtain the requisite purity and softness. Indeed, the cost of the water alone may in large measure determine the commercial success or failure of a given plant.

In the ordinary discontinuous systems of manufacturing multiple filament viscose artificial silk thread; i. e., the pot-spinning and spool-spinning systems, the thread is subjected to the action of the processing liquids while it is wound in the original spin cake or spool package. That is, the thread is treated with liquids while wound in a compact package containing thousands of yards of thread wound layer upon layer. Of a given amount of liquid applied to the thread package, most serves to process the thread; but it is known that, due to difficulties of penetration of the processing liquid, all portions of thread in the package are not uniformly processed.

In continuous processing operations, on the other hand, the thread is continuously but temporarily stored on one or more thread-advancing, thread-storage devices, being subjected to the action of processing liquids while in the form of a helix made up of a large number of closely spaced turns.

As compared with discontinuous systems, the advantages of manufacturing multiple filament viscose artificial silk thread by a system involving the continuous processing of the thread are so great as to have served in the past as an incentive for numerous attempts to devise a successful continuous processing system. It has long been recognized that a continuous system of manufacturing multiple filament viscose artificial silk thread would possess advantages over discontinuous systems in making possible great savings in time and labor, this for the reason that the numerous processing treatments which

must be applied to the thread may be performed continuously on a single machine. A continuous manufacturing system would possess great advantages as regards thoroughness and uniformity of processing because the thread is subjected to the processing treatment while wound in a single layer and is not processed, as in the discontinuous processes, while wound in package form.

It has, however, been found that systems involving the continuous processing of the thread are often less economical in their use of processing liquids than discontinuous systems. This arises in part from the fact that in continuous systems the thread is processed while wound in a single layer. All of the liquid applied to the thread is not used in the actual processing of the thread; instead, part of the liquid runs off the thread-advancing, thread-storage device and part passes between the turns of thread.

Other disadvantages have been found to arise from the fact that in some continuous processing systems intermixing of the processing liquids tends to occur.

The present invention, by eliminating difficulties arising out of the tendency of continuous processing systems to use more processing liquids to process a given amount of thread than discontinuous systems, provides an economy of consumption of processing liquids comparing very favorably with that of the discontinuous systems.

While continuous processing systems make possible more uniform processing of the thread than do discontinuous processing systems because the thread is processed while stored in a single layer, it is extremely important that predetermined constant amounts of processing medium be supplied over long periods of time to the thread stored on each thread-advancing, thread-storage device; also, that if a large number of threads are processed, all corresponding thread-advancing, thread-storage devices be supplied with processing medium at identical rates in order to prevent the occurrence of thread-to-thread variations in processing. The importance of such uniformity in the rate of supply of processing media is emphasized by the fact that the thread is usually subjected to the processing media for a matter of seconds, at the most a minute or two, and hence any change in the rate of supply of the processing media to the thread will be reflected as a change in the physical or physico-chemical characteristics of the finished thread. That is, in continuous processing operations, because of the necessity of rapidly processing the

thread, there is no such factor of safety as in the discontinuous process, wherein the thread is subjected to each processing liquid for a period of several hours.

The present invention provides a circulation system which makes it possible accurately to supply a predetermined amount of processing liquid at a constant rate of flow to a single thread-advancing, thread-storage device or to a plurality of thread-advancing, thread-storage devices. In the latter case, the invention makes it possible to supply all of the thread-advancing, thread-storage devices with identical amounts of processing liquid at an equal rate of flow. According to the invention, moreover, intermingling of the various processing liquids is prevented, whereby the possibility of contamination of the liquid is obviated.

For the purposes of illustration, the invention will be described hereinafter in connection with the manufacture by a continuous system of multiple filament viscose artificial silk thread on apparatus generally similar to that shown, described, and claimed in copending application Serial No. 7,114, filed February 18, 1935, by Walter F. Knebusch and Alden H. Burkholder (Patent 2,225,642). It should, however, be understood that the present invention is not limited thereto, but that in certain aspects it may be employed in the continuous processing of thread produced by other methods as, for example, from casein, cellulose acetate, cuprammonium cellulose solutions, etc. As indicated above, the present invention is applicable not only to the processing of multiple filament artificial silk thread but to the processing of thread-like articles generally.

The drawings show the invention as applied to the apparatus of the above-identified application in connection with the manufacture by a continuous system of multiple filament viscose artificial silk thread.

Figure 1 is an end elevation of a complete thread-processing machine of the kind described in said prior application, the means for applying processing medium to the thread on the thread-advancing, thread-storage device being omitted and other parts being broken away for the sake of clearness. Figure 2 is an end elevation corresponding generally to Figure 1, but on a larger scale, of a portion of the machine with parts broken away more clearly to show the mechanism. Figure 3 is an elevation on the same scale as Figure 2 of one operating face of the machine, corresponding generally to the operating face on the right of Figure 1, parts being broken away for the sake of clearness.

Figure 4 is an elevation of the apparatus on the same scale as Figure 3 and line 4-4 thereof showing processing liquid circulation apparatus embodying the present invention. Figure 5 is a detail sectional elevation from line 5-5 of Figures 3, 6 and 7 through a thread-advancing reel typical of the thread-advancing, thread-storage devices employed in the illustrated apparatus. Figure 6 is an end elevation of the reel of Figure 5 on the same scale and from the left end thereof. Figure 7 is a detail plan on a slightly smaller scale than Figures 5 and 6 illustrating several of the thread-advancing reels and associated apparatus shown in Figure 5, the covering of the gear housing being omitted.

Figure 8 is a somewhat diagrammatic representation of the circulation apparatus illustrated in the above figures, said figure including one reel of a horizontal series of corresponding reels and

its associated processing liquid circulating apparatus as viewed from the front of the continuous processing apparatus, parts being broken away for the sake of clearness. Figure 9 corresponds to a sectional elevation of the apparatus shown in Figure 8. Figure 10 is a somewhat diagrammatic representation, generally similar to Figure 8, illustrating a modified type of circulating system embodying the present invention. Figure 11 is a sectional elevation of the apparatus shown in Figure 10, parts being broken away.

In the drawings, like reference characters refer to like parts throughout.

In the apparatus shown in Figures 1 to 4, inclusive, the thread 1 is formed by extrusion of the viscose into the coagulating bath 2 through a suitable spinneret 3, passing therefrom through a guide 4 to a thread-advancing reel of cantilever form, designated 5, from which it passes to any suitable number of other like reels 5a to 5i upon which are performed any desired processing steps. The cantilever construction of one of the reels is shown in detail in Figure 4 and will be described more in detail hereinafter. The thread is led from the last reel 5i through a suitable guide 6 to a collecting device such as cap-twister 7.

The production of each multiple filament thread requires a complete series of such thread-advancing reels in numbers sufficient to enable the desired processing steps to be performed on the thread. However, a given machine may be built to provide for the simultaneous production of a multiplicity of such threads. Thus each machine may include a plurality of series arranged in such manner as to enable the parts thereof to be conveniently accessible for inspection, manipulation or control, as well as to enable the plurality of such series to be driven from the same power source.

In the illustrated machine, the reels are shown as arranged in a plurality of descending series on each of which the thread is subjected to the desired processing treatments. Since the reels are of cantilever form; i. e., supported and driven from one end only, and since the thread is, by the action of the reels, advanced axially thereof toward the free end thereof, they may be positioned, as shown, in stepped arrangement with the receiving end of each reel immediately below the discharge end of the next preceding reel. The open ends of the reels, constituting the discharge ends, are presented to the operator. This arrangement provides advantages in construction of the processing apparatus as well as advantages in permitting access to the reels for manipulation of the thread, inspection, repairs, etc.

Furthermore, it has been found desirable to position the reels in adjacent series so that corresponding reels are in corresponding positions. Thus the reels are in effect disposed in a plurality of horizontal series extending longitudinally of the machine. This disposition of the reels in what may be regarded as a plurality of longitudinal series results in simplification of the construction of the processing medium supply and removal systems as well as advantages in driving the thread-storage reels, as will be hereinafter explained more in detail.

Furthermore, the machine may, as shown in Figure 1, be double-sided, having a plurality of thread-storage devices disposed in an inclined bank on each side of the machine.

The machine shown in Figures 1 to 4, inclusive, comprises a suitable frame including lower and

upper platforms 8 and 9 carried by cross beams 10 and 11 supported by corner posts 12, the platforms 8 and 9 being connected by diagonal uprights 13 and 14. The drive mechanism for the reels may have as a source of power a drive motor 18 which may be mounted at one end of the machine, as shown in Figure 3. The shaft of such motor actuates a suitable speed reducing device 19 operating a cross shaft 20 provided at its opposite ends with bevel gears 21 which mesh with bevel gears 22 on diagonal shafts 23, of which one may be provided on the left side and one on the right side of the machine as shown in Figure 1.

Diagonal shafts 23 are in the illustrated embodiment of the invention provided at various levels with take-off drives for the reels 5a and 5i, inclusive. The driving connections to the several reels may, if desired, include any suitable form of change speed mechanism. For convenience, the shafts 23 and the drive connections therefrom to the several reels may be located at one end of the machine, as shown in Figures 2 and 3.

As the drive connection from the primary drive shaft 23 to each of the reels 5a to 5i is the same, description of one will suffice for all. Thus, for the drive to each of the reels 5a and 5i, drive shaft 23 drives short shaft 62 (Figures 2 and 3) through suitable gears contained in the housing 62a. Shaft 62 drives shaft 67 through suitable change speed mechanism indicated generally as 66, said shaft 67 extending horizontally and longitudinally along the operating face of the machine and being provided with suitable driving means for the corresponding horizontal or longitudinal series of reels disposed along the shaft.

The means for driving each reel from said shaft 67 is shown to better advantage in Figures 5 and 7. As shown, the driving means may be enclosed in a longitudinally extending housing 76 which may also serve as a lubricant reservoir for the parts therein and which may be provided with a removable cover 77. Drive shaft 67 extends longitudinally of the housing, its outwardly projecting ends being connected by couplings 75 (Figure 3) to like ends of neighboring shaft sections. The shafts 72 for the reels are journaled in opposite walls of said housing, crossing said drive shaft 67.

In the apparatus shown, each reel in the horizontal series is mounted on one face of the housing 76 and is driven from secondary drive shaft 67 by a spiral gear 70 engaging a spiral gear 71 rotatably mounted on reel drive shaft 72. Spiral gear 71 is provided with a clutch member 73a cooperating with a slidable clutch member 73b splined to the shaft 72 actuated by a controlling bell crank lever 74. Figure 5 shows the clutch members in engagement, so that the reel shaft 72 may be rotated. Each reel may thus be provided with its individual clutch and the levers 74 for all reels may be individually operated; however, for convenience the levers 74 for reels 5a to 5i of a vertical series may be connected together so that all of the reels in one vertical series may be started and stopped simultaneously.

The thread-advancing, thread-storage devices of the instant apparatus take the form of a reel of the type shown in Figures 5 and 6, which is of the same general form and operates in the same manner as the reel shown, described, and claimed in a prior application entitled "Winding reel for spinning machine," Serial No. 652,089, filed January 16, 1933, by Walter F. Knebusch (Patent 2,210,914). The reel shown is, however, of canti-

lever form in the sense that the supports for said reel are connected to it at one end only, leaving the thread-supporting bars free and open at the other end of the reel. Therefore, by rotating the reel in the proper direction to cause the turns of thread to travel from its driven end to its free end, the task of transferring the thread from reel to reel is materially simplified due to the absence of a shaft extension and consequent ease of manipulation of the thread by the operator.

The typical form of reel shown in these figures includes two rigid, generally cylindrical members respectively designated 80 and 81. Member 80 may be termed the concentric member because it is concentric with, fixed to, and rotates with the reel shaft 72. Member 80 includes a body portion of generally cylindrical form with its periphery slotted to form a series of alternating bars 82 and recesses 83, the body portion being mounted upon a sleeve 84 keyed to the shaft 72 and held in place thereon by a nut 85 threaded upon the end of said shaft. The other member 81 of the reel may be called the eccentric member, because while it is generally of cylindrical form it is mounted with its axis laterally offset slightly from and disposed askew or inclined to the axis of the shaft 72. The member 81, as shown, comprises a head formed of inner and outer rings 87 and 88, the former of which has peripheral slots to receive the bars 89. The bars are clamped between the rings 87 and 88, which are held together by screws 81a. Inner ring 87 is mounted on a sleeve 90 journaled to rotate upon a supporting member 91 which surrounds shaft 72 and is spaced therefrom. Means are provided for supporting member 91 with its axis slightly offset laterally from and inclined with relation to the axis of shaft 72.

Rotation of the drive shaft 72 causes concentric member 80 fixed thereto to rotate, whereupon contact of bar members 82 of concentric member 80 with bar members 89 of eccentric member 81 causes said eccentric member to rotate. The thread is thus caused to wind on the reel, the degree of the inclination of the reel members with respect to each other determining the lead or pitch of the turns of thread wound in generally helical form upon the reel and progressively advanced along it. With a reel of this general type, any desired length of thread within reasonable limits may thus be continuously but temporarily stored in a plurality of advancing turns.

Reels of the form shown in Figures 5 and 6 may be employed for each of the reels 5 to 5h, inclusive, Figure 1, since it may be desirable to apply wet processing treatments to the thread while stored on these reels. However, it may be desired to dry the thread on the reel 5i before it is collected, as by cap-twister 7, in which case the reel 5i, while of the same general type and operating in the same general manner as the others, may be adapted to supply drying medium to the thread stored on the reel from the interior of the reel. Such a reel is described in detail in said prior application Serial No. 7,114.

Each descending series of reels is identified with one of the cap-twisters 7 shown as the collecting means in the illustrated apparatus. A plurality of said cap-twisters 7 is driven by the same power source. The illustrated apparatus is provided with a long drum 119 connected by belts 120 to the whirls supporting the bobbins of the twisters, belts 120 being provided with belt tighteners 120a. Drum 119 is driven by a belt 121

actuated from the drive shaft of the speed reducing mechanism 19 which is driven by motor 18.

For reciprocating the twister bobbins, a speed reducing device 122 is provided driven by a belt 123 from a pulley on shaft 20. The shaft 124 of said speed reducing device is provided with a cam 125 actuating a lever 126 pivoted on the frame at the point 127 and connected by tension members 128 to lifting rods 129 slidably vertically in frame guides 130 and connected by beams 131 rotatably carrying the bobbins, the vertically moving parts being at least partly counterbalanced by weights 132. The function of drums 119 and cams 125 is to rapidly rotate and vertically reciprocate the bobbins of the several cap-twisters, so that the thread is twisted and wound in the desired form thereon.

Means are provided for subjecting the thread on one or more of the reels 5a to 5h to suitable wet processing operations; to wit, means disposed above each of said reels for supplying to said reel processing liquid in the form of a spray or one or more small streams, a trough disposed beneath each of said reels for collecting the processing liquid as it drains from the reel, and apparatus for recirculating the liquid. By reference to Figures 2, 3 and 7, it can be seen that each of said troughs 108 may be suitably formed to collect the liquid and prevent splashing thereof and may be provided with a re-entrant portion 118 below each reel to allow travel of the thread from an upper reel to a lower reel. Because of the arrangement of the reels in a plurality of horizontal or longitudinally extending series, it is possible to have each trough 108 serve several corresponding reels in adjacent processing series.

Likewise, the liquid distributing system may serve corresponding reels in adjacent series. In the illustrated embodiment, a suitable reagent distributor 115 is positioned above each reel on which processing liquid is applied to the thread, the reagent distributor 115 being supplied from a common supply conduit 113 extending longitudinally of the machine and serving the reagent distributors for the corresponding reels in a horizontal series.

In the embodiment of the invention illustrated in Figures 3, 4, 8 and 9, each horizontal series of corresponding reels on which processing liquid is to be applied to the thread is supplied with processing liquid through a supply conduit 137. The latter communicates with a constant head supply box 138 associated with said series. A valve 139 may be provided in said supply conduit 137 to control the amount of liquid passing to the supply box 138. Supply box 138 communicates with the horizontally extending conduit 113 which supplies the reagent distributors 115 for said horizontal series of reels from tubes 114.

The level of processing liquid in the supply box 138 is maintained at a predetermined height above the orifices from which the liquid discharges to the reels from said conduit 113 by suitable overflow means associated with said supply box. In the illustrated apparatus, supply box 138 is provided with an extended portion 141 having connected thereto an overflow pipe 142. Processing liquid which is supplied to said constant head supply box 138 in excess of the amount which passes to the reagent distributors supplied from said supply box 138 overflows through said overflow pipe 142, thus maintaining a constant level of liquid in said supply box.

The orifices in tubes 114 through which the processing liquid leaves the conduit 113 to pass

to the reels of the horizontal series are preferably all of the same size and disposed substantially on the same level, so that all reels in said horizontal series are supplied with substantially identical amounts of processing liquid. Due to the relatively low rate of flow of the processing liquid through the conduit 113 and the relatively large diameter of the supply conduit 113 as compared with the size of said orifices, very little, if any, loss of pressure results from one end of conduit 113 to the other.

The collecting troughs 108 for each horizontal series of reels extend, as has been explained, under a plurality of reels in said horizontal series, adjacent troughs being connected together. Therefore, all of the liquid which has been supplied from the conduit 113 to a horizontal series of reels may be collected in the troughs 108 below the reels and passed through the corresponding conduit 143 which communicates with the overflow conduit 142. The combined liquid may then pass, as diagrammatically shown in Figure 8, to one or more supply tanks 144. From said supply tanks the processing liquid may be pumped, as by pumps 145, back up to the constant head supply box 138 through conduit 137.

It is desirable to provide a plurality of said supply tanks and pumps, as shown, so that factors causing one of said supply tanks or pumps to be taken out of commission will not cause shutting down of the apparatus. In ordinary operation, indeed, it is desirable to use at least one of said supply tanks and pumps as a standby unit. Suitable valves 146 and 147 may be provided to put in or take out certain tanks from the system. Similarly, valves 148 may be provided to make it possible to cut out each of the pumps or to control the amount of liquid flowing therethrough. A direct connection 149 to the sewer from each tank 144 may also be provided, as that controlled by valve 150 in the apparatus shown, to make possible flushing of the tanks 144 or discharging of the spent liquid therefrom to the sewer.

Preferably the amount of processing liquid supplied to constant head supply box 138 is only slightly greater than the amount which passes therefrom to the reagent distributors through conduit 113. Only a small amount of overflowing takes place; in fact, only sufficient to maintain the level of liquid in the constant head supply box 138 constant. The amount of liquid flowing into container 138 may be controlled by valve 139.

The pumps 145 are preferably of the impositive delivery type, so that controlling of the amount of liquid flowing therethrough by adjustment of the valve 139 will not cause difficulties due to excessive pressures. Desired make-up additions may be made from time to time or continuously to tanks 144, in which tanks tests may also be made from time to time to determine the strength of the solution. In the apparatus of Figures 8 and 9, inlet pipe 151, controlled by valve 152, is provided for making possible the addition of liquid to the system. Preferably, tanks 144 and pumps 145 are located below the floor on which the machine is mounted. For this reason, the conduits 137 and 142 in Figures 3 and 4 are shown as extending only to the floor.

In the modification shown in Figures 10 and 11, processing liquid is supplied from tanks 144a by means of pumps 145a and conduit 137a. Valve 139a is provided in said conduit to control the quantity of liquid flowing therethrough. As

in the preceding embodiment of the invention, conduit 137a is connected to a container 138a. However, conduit 137a is also connected to longitudinally extending conduit 113 from which the reels are supplied, as through conduit 153. Thus part of the liquid supplied through conduit 137a passes into container 138a and part into conduit 113. The V-connection between conduit 153 and conduit 137 is not absolutely necessary, but is desirable in providing for a smoother flow of liquid.

From container 138a the liquid overflows from extended portion 141 of said container into conduit 142a, being combined with the liquid collected in trough 108, which collected liquid passes through conduit 143a to conduit 142a. The combined liquid then passes back to tanks 144a. Valves 146a and 147a may be provided, as shown, to make it possible to cut out any of tanks 144a, while valves 148a may be provided to make it possible to cut out one or more of the pumps 145a or to control the liquid flow therethrough. Similarly, a connection 149a controlled by valve 150a, may be supplied to provide for discharging liquid from any of the tanks 144a to the sewer, while pipe 151a and valve 152a may be provided to make possible the addition of liquid.

In the operation of the apparatus shown in Figures 10 and 11, liquid is supplied through conduit 137a in an amount in excess of the amount which flows through conduit 113 to the reagent distributors for the reels. The excess liquid flows into container 138 and out through overflow conduit 142a, which thus maintains a constant liquid level in the container. The liquid which has been applied to the reels and collected in the coagulating trough 108 passes through conduit 143a and is combined with the overflow in conduit 142a. Since the system is open in the container 138, a constant predetermined pressure is maintained in the conduit 113, being determined by the level of liquid in container 138, from which conduit 113 the processing liquid is discharged onto the reels.

Preferably, as in the preceding embodiment of the invention, the orifices along the length of conduit 113 are of the same size and substantially on the same level, so that all corresponding reels in the horizontal series associated with the container 138 may be supplied with substantially, if not wholly, identical quantities of liquid flowing at constant rates. If, for instance, a momentarily greater quantity of liquid should be supplied through conduit 137a, such excess amount passes into container 138 and down through overflow conduit 142a, rather than into conduit 113. A constant pressure is thus maintained on the processing liquid distributors in this embodiment of the invention.

In the embodiment of the invention shown in Figures 3, 4, 8 and 9, the constant head supply boxes and piping therefor for the various processing liquids are disposed at one end only of the apparatus. As shown, they are mounted at the end of the apparatus opposite the drive end, since advantages in construction are thereby provided. The constant head supply boxes are disposed in stepped arrangement corresponding generally to the stepped arrangement of the reels with which they are associated and are mounted on an inclined beam 154 which is spaced from and connected to the frame of the apparatus. However, in the illustrated apparatus, each bank of reels on the apparatus is provided with its own circulating system, a space being left between the

piping for the opposite banks. This space permits access to the interior of the apparatus from the liquid supply end of the apparatus.

It is apparent that circulation apparatus embodying the arrangement of Figures 10 and 11 can be readily constructed with its containers 138 and processing liquid supply and drain conduits 137a and 142a in an arrangement generally similar to that of the constant head supply boxes 138 and conduits 137 and 142 of the other embodiment of the invention.

Each of the forms of apparatus illustrated as embodying the invention thus makes it possible to maintain a constant predetermined pressure on the processing liquid distributing system of each horizontal series of reels on which liquid is applied to the thread. Identical constant pressures may thus be maintained on all discharge orifices from which processing liquid is supplied to all reels in a horizontal series, so that identical amounts of processing liquid may be supplied to such reels at constant rates of flow. Extremely uniform processing of the thread is therefore made possible because the constant rate of flow of each processing liquid insures that all portions of the same thread are subjected to identical treatments and because all threads may be subjected to identical quantities of each processing liquid.

Constant pressure is maintained in each of the illustrated embodiments by maintaining a constant level of liquid at a predetermined height, overflow means being employed to insure that the level of liquid is constant. In each case, the overflowing liquid and the liquid which has been applied to the reels and collected is combined and recirculated back to process more thread. Thus excellent economy in the consumption of processing liquids is provided by the present invention, since the liquids may be re-used several times. Moreover, since the various processing liquids are applied to the thread on different reels and since each processing liquid may circulate through an individual system, intermingling, and hence contamination, of the different processing liquids may be prevented.

It is apparent that various modifications may be made in the illustrated embodiment and that the invention may be applied to other uses than that in connection with which it has been described above without departing from the spirit of the invention. In the appended claims the term "thread" is intended to mean, besides per se, all other materials capable of being handled and processed by means embodying the present invention. It is intended that the patent shall cover, by suitable expression in the appended claims, whatever features of patentable novelty reside in the invention.

60. What is claimed is:

1. Apparatus for the continuous processing of thread comprising a plurality of series of thread-storage devices each of which series processes a single thread; means for applying processing liquid associated with each thread-storage device on which processing liquid is to be applied to the thread; a conduit connected to the processing liquid applying means for each set of corresponding thread-storage devices of said series of devices, said conduit being adapted to direct upward an amount of processing liquid in excess of the amount which passes to said processing liquid applying means; a second conduit connected to said first-mentioned conduit conducting processing liquid to a surface positioned at

a predetermined height above said processing liquid applying means over which surface the excess processing liquid flows, the amount of liquid flowing thereover being independent of the presence of thread on said thread-storage device; means for collecting the processing liquid which has been applied to said set of corresponding thread-storage devices; and means for combining said collected processing liquid with the processing liquid which overflows said surface and passing said combined processing liquid to the first-mentioned conduit for one of said sets of corresponding thread-storage devices.

2. Apparatus for the continuous processing of thread comprising a thread-advancing, thread-storage device which continuously but temporarily stores the thread in a plurality of spaced, generally helical turns; means for applying processing liquid to the thread while it is stored on said thread-advancing, thread-storage device; a conduit connected to said processing liquid applying means adapted to direct upward an amount of processing liquid in excess of the amount which passes to said processing liquid applying means; a second conduit connected to said first-mentioned conduit conducting processing liquid to a surface portioned at a predetermined height above said processing liquid applying means over which surface the excess processing liquid flows, the amount of liquid flowing thereover being independent of the presence of thread on said thread-advancing, thread-storage device; means for collecting the processing liquid which is applied to said thread-advancing, thread-storage device; and means for combining said collected processing liquid and the processing liquid which overflows said surface and passing the combined processing liquid to said first-mentioned conduit.

3. Apparatus for the continuous processing of thread comprising a plurality of descending series of thread-advancing, thread-storage devices each of which series processes a single thread, said series being disposed adjacent each other in the form of a longitudinally extending bank; means for applying processing liquid associated with each of a plurality of thread-advancing, thread-storage devices in each series; supply means disposed in stacked relation at one end of said bank for supplying processing liquid at a constant pressure to the processing liquid applying means for each set of corresponding thread-advancing, thread-storage devices of a plurality of series, each of said supply means including means directing upward an amount of processing liquid in excess of the amount which passes to said processing liquid applying means and a surface positioned at a predetermined height above said processing liquid applying means and associated with said processing liquid directing means over which surface the excess processing liquid flows; means for collecting the processing liquid which has been applied to said corresponding thread-advancing, thread-storage devices; means for combining said collected processing liquid with the processing liquid which

overflows said surface; and means for recirculating the combined processing liquid to said supply means.

4. Apparatus for the continuous processing of thread comprising a plurality of descending series of thread-advancing, thread-storage devices each of which series processes a single thread, said series being disposed in the form of a longitudinally extending bank; a container from which processing liquid is supplied to each set of corresponding thread-advancing, thread-storage devices in said plurality of series, said container being provided with overflow means for maintaining a predetermined level of processing liquid in said container; means for supplying processing liquid to said container in excess of the amount which is supplied to said thread-advancing, thread-storage device, said supply means communicating with said container below the surface of the liquid in said container; means for mounting said containers and supply means at one end of said bank, the containers being disposed in stacked relation; means for collecting the processing liquid which is supplied to each set of said thread-advancing, thread-storage devices; means for combining said collected processing liquid and the processing liquid which overflows from the corresponding container; and means for passing said combined processing liquid to the container for one of said sets of corresponding thread-advancing, thread-storage devices.

5. Apparatus of the character described in claim 4 in which said last-mentioned means passes the combined processing liquid to the container in which it originated.

6. Apparatus for the continuous processing of thread comprising a bank of thread-advancing, thread-storage devices which includes at least one descending series of such devices adapted to process at least one thread; means for applying processing liquid to the thread stored thereon associated with each of a plurality of thread-advancing, thread-storage devices in said series; supply means disposed in stacked relation at one end of the bank for supplying processing liquid at a constant pressure to each of said processing liquid applying means, each of said supply means including means directing upward an amount of processing liquid in excess of the amount which passes to said processing liquid applying means and a surface positioned at a predetermined height above said processing liquid applying means and associated with said processing liquid directing means over which surface the excess processing liquid flows; means for collecting the processing liquid which has been applied to each thread-advancing, thread-storage device; means for combining the collected processing liquid with the processing liquid which overflows said surface; and means for passing the combined processing liquid to one of said processing liquid supplying means.
